INDENTING MACHINE

Frank Bycroft Keall, Leicester, England, assignor
to United Shoe Machinery Corporation, Paterson, N. J., a corporation of New Jersey

Application May 1, 1934, Serial No. 723,344
In Great Britain May 10, 1933

24 Claims. (Cl. 12—32)

This invention relates to finishing machines and is herein illustrated as embodied in a machine of the type disclosed in United States Letters Patent No. 958,913, granted on May 24, 1910, in the name of L. W. G. Flynt.

Machines of this type are commonly employed in making shoes for the purpose of imparting a series of decorative indentations to the upper marginal surface of the portion of a shoe which

10 projects laterally from the upper.

In the use of a machine of the type disclosed in the above-mentioned patent, a continuously rotated tool is caused both to indent the upper surface of the welt of a welted shoe or the similar surface of a shoe having an other-than-welt construction and also to effect a feed movement of the shoe which is supported beneath the tool by a work rest which rotates freely in response to the feed movement imparted to the shoe by the tool. Moreover, it is recognized by those skilled in this art that whereas the indenting operation can be performed satisfactorily while employing a substantially constant indenting pressure, the operation can nevertheless be performed quicker and more effectively if the indenting pressure is applied as by a rapid succession of short im-

5 pulses.

Accordingly, an object of the invention is to provide an improved machine having both these operating characteristics in the construction of which the difficulty of positively rotating a tool which at the same time is vibrated rapidly in a direction extending transversely of its axis is overcome. To this end, the machine in which the invention is illustrated as embodied comprises a work rest, a rotating tool shaft carrying an indenting tool and mounted for movement toward and away from the work rest, means for continuously rotating the shaft, and means for 10 positively moving the shaft directly toward and away from the work rest to cause the tool to beat against a work piece on said work rest. Such a machine answers the requirements referred to above by providing an uninterrupted feeding movement of the work derived from the continuous rotation of the tool itself while the latter is moved alternately in opposite directions normal to the surface of the work rest opposite to the tool.

15 The above-mentioned movement of the tool is permitted by mounting the tool shaft for movement toward and away from the work rest in a direction extending transversely of the axis of the shaft and the invention, in another aspect, 20 contemplates the provision, with the shaft mount-

ed as above described, of crank operated means for moving the shaft as described above toward and away from the work rest to cause a rapid succession of blows to be imparted by the tool to a work piece on the work rest.

25 The crank operated means referred to above, as herein illustrated, comprises a connecting rod and a crank for operating the connecting rod, the connecting rod being constructed and arranged, in one illustrative embodiment of the invention, to reciprocate a slide in which the indenting tool is rotatably mounted, and in another embodiment of the invention, bodily to swing the shaft carrying the indenting tool, the tool shaft in this case being mounted to swing transversely of its axis about a point at its axis remote from the tool.

30 Variations in the thickness of shoe parts, as indented in prior machines of which applicant is aware, result in corresponding differences in the amount of indenting pressure exerted by the tool against the work. That is, thick portions of the work receive a greater indenting pressure than thin portions of the work whether the support for the work is arranged resiliently to yield or is adjustably fixed, with regard to its position relatively to the tool. Excessive indenting pressure may crush the work; and if the indenting pressure is inadequate, the regularity of the indentations will be impaired.

35 With the foregoing in view, another object of the invention is to provide an improved work supporting mechanism the use of which with an indenting tool insures uniformity in the indentations.

40 To this end, the invention provides in an indenting machine having an indenting tool and a work rest mounted for movement toward and away from the tool, operator-controlled means for moving the work rest toward the tool to cause indenting pressure to be applied to a work piece therebetween, and a yielding support for the operator-controlled means arranged to resist the 45 said indenting pressure with a substantially constant force throughout a limited range of movement of the work rest. This limited range of movement of the work rest is great enough to include the normal and usual variation in work pieces upon which the indenting operation is performed. Uniformity in the indenting pressure is obtained in the illustrated machine, irrespective of normal variations in the thickness of the work, by utilizing the gravitational effect of a weighted member, a lever in the illustrated embodiment of the invention, which is mounted 50 55

to swing about its fulcrum in response to variations in the thickness of the work.

For the purpose of facilitating the insertion of a work-piece to be operated upon between the work rest and the tool, the above-mentioned means for moving the work rest preferably and as herein illustrated includes, as an important feature of the invention, connections between the rest and the weighted member arranged normally to hold the rest in its inoperative position but operable also in opposition to the gravitational effect of the weighted member to cause it to set up an indenting pressure between the tool and a work-piece which has been carried into engagement with the tool.

Even a normal indenting pressure, if imparted by an indenting tool against a work piece having an abnormally soft portion, will crush the work piece at this location to the detriment of the shoe. Accordingly, it is desirable that the indenting pressure in such a case be relieved when the tool encounters a soft spot before damage can be done to the work. To this end, the movement of the weighted member referred to above is so limited in the illustrated machine by a stop as to prevent the exertion of any additional pressure after the greatest, safely allowable penetration of the tool into the work has occurred.

These and other features of the invention will now be more fully set forth in the following specification with reference to the accompanying drawings, in which:

Fig. 1 is a front elevation of one illustrative embodiment of the invention, a part of this view being in section;

Fig. 2 is a fragmentary sectional view taken along the line II—II in Fig. 1;

Fig. 3 is a view in side elevation of the machine illustrated in Fig. 1, a part of this view being shown in section, and

Fig. 4 is a sectional side elevation illustrating another embodiment of the present invention.

As shown in the drawings the actual work-rest is in the form of a freely rotatable disc 10 mounted adjustably for tilting about a horizontal axis upon an arcuate member 12 held in an arm 14 which is pivoted to the rear of the machine frame 15 at 16. The disc 10 is adapted to support a shoe by engagement with the tread surface of the sole in such manner that the upper margin or "welt" of the shoe sole is presented to the action of a toothed wheel 18 which is continuously rotated by power and also receives small but rapid vertical reciprocations as will be fully explained hereinafter. A pair of guiding fingers 21 are placed so as to have contact with the upper of the shoe being treated and aid to prevent scoring of the upper by the end of the wheel 18.

The member 12 rests upon the upper end of a plunger 22 which is mounted to slide vertically in a guide 24 fixed to the machine frame 15. The plunger 22 has a threaded stem 26 entering a sleeve 28 having a knurled hand nut 30 which rests upon a horizontal face of a member 32 having a stem 33 which enters a bore in the sleeve 28. By turning the nut 30 the plunger 22 may be adjusted vertically so as to adjust the distance between the top of the disc 10 and the underside of the indenting wheel 18, in accordance with the thickness of the work to be treated.

The member 32 is connected by links 34, 36 to a pivot pin 36 in a support-controlling lever 38. This lever 38 is pivoted upon a circular boss 40 which is in turn pivoted to the machine column

42 about a stud 43 the centre of which is offset a small distance laterally from the centre of the boss 40. The links 34 and the arm of the lever 38 to which they are attached thus constitute a toggle which when collapsed, as when the lever 38 abuts a stop 58 mounted for adjustment in a lug extending laterally from the column 42, causes the work rest 10 to be held in its inoperative position, that is, retracted from the tool 18 so as to eliminate the necessity for treading the machine 10 to permit the work to be inserted between the tool and the work rest. Fixed to or integral with the boss 40 is an arm 44 adapted to carry a weight 46 the position of which on the arm is adjustable. Projecting from the side of the column 42 is an arm 48 carrying a stop 50 arranged to limit the downward movement of the arm 44. One end of the lever 38 is connected at 52 by an adjustable tie-rod 54 to a treadle (not shown). A spring 56 connecting the lever 38 and the machine column 20 42 normally pulls the lever 38 upwardly into contact with the stop screw 58.

A spring and stop corresponding to 56 and 58 may be attached to the treadle itself instead of to the lever 38 as shown.

In the machine illustrated in Figs. 1, 2 and 3, the indenting wheel 18 itself is fixed on the outer extremity of a shaft 60 which is rotatably mounted in a sliding bearing block 62. The bearing block is rapidly reciprocated, directly toward and away from the work support 10, by a connecting rod 64 which is attached to the block 62 by a bolt 66 and is mounted on an eccentric 68 formed on one end of a shaft 70 journaled in the upper part of the frame 15. The other end of the shaft 35 70 carries a pulley 72 and in the normal operation of the machine is to be driven by a belt or other convenient driving means at a speed in the vicinity of 2000 R. P. M. The eccentricity of the eccentric 68 should be determined with reference to the type of work for which the machine is to be used, and the pitch of the indenting teeth on the wheel 18, and may be in the vicinity of 1 mm. for example. The bearing block 62 is guided by ways 74 formed in the front portion of the machine frame 15 and plates 67 which are secured to the frame 15 adjacent to the ways, as indicated in Fig. 2.

While the indenting wheel 18 is thus rapidly reciprocated, it is also continuously rotated. The wheel 18 is thus driven from a shaft 78 journaled in the frame 15 through connections of the type known as an Oldham coupling comprising a member 80 having a spline 82 which is received in a keyway in a flanged member 84 which is pinned to the end of the wheel shaft 60 remote from the wheel 18. The member 80 at the side opposite to the spline 82 is grooved to receive a spline 86 at right angles to the first spline and extending from the radial surface of a flange 88 integral with the shaft 78. A driving connection is thus maintained between the shaft 78 and the wheel shaft 60 notwithstanding the reciprocation of the latter. The shaft 78 carries a spur gear 90 which is driven by a pinion 92 fixed to a drive shaft 94 carrying at its outer end driving and idling pulleys 96, 98, respectively, which are to be driven by a belt for example at such a speed as to cause the indenting wheel to be rotated at approximately 70 60 R. P. M.

If desired, the alternative form of indenting wheel operating mechanism illustrated in Fig. 4 may be employed in connection with the work supporting mechanism referred to above, instead 75

of the indenting wheel mechanism just described. This mechanism, as illustrated in Fig. 4, comprises a tool shaft 100 on which is rotatably mounted a spur gear 102, the latter being positively driven by a pinion 104 fixed to the inner end of a drive shaft 106. A driving connection between the gear 102 and the shaft 100 can be obtained by a clutch mechanism 108 which is actuated by a forked lever 110. Except as will be pointed out hereinafter, the construction referred to above is substantially the same as that disclosed in the above-mentioned Flynt patent, to which reference may be made for a more detailed description of the parts common to both of these constructions. The end of the tool shaft 100 adjacent to the indenting tool 112 has formed thereon a spherical bearing surface 114 which is engaged by a complementary surface formed within the lower end of a connecting rod 116 which, for the sake of convenience in manufacture, is made in two parts which are secured together by screws 118. The connecting rod 116 is driven at its upper end by an eccentric 120 on a shaft 122 the end of which opposite the eccentric carries a pulley 124 which is to be driven at a speed in the vicinity of 2000 R. P. M., as in the case of the similar shaft in the construction illustrated in the other figures. The tool shaft 100 is supported at the end adjacent to the tool against vertically directed pressures by the connecting rod 116 and against laterally directed pressures by a bearing 126 which is so shaped as to have line contact with the shaft 100 at the sides and is relieved at the top and bottom in accordance with the eccentricity of the eccentric 120 whereby the shaft 100 is guided laterally but is permitted to rise or fall in response to the action of the connecting rod 116. The tool shaft 100 is supported at its end remote from the tool by a bearing 128 the bearing surface of which is tapered somewhat as shown by exaggeration in Fig. 4 so as to allow the tool shaft 100 to swing about a point at its axis and within this bearing. The throw of the eccentric 120 being relatively small, about .020 of an inch, it is apparent that the curvature of the bearing 128 may be very small and that the effective bearing surface presented by the bearing 128 is not materially diminished as a result of this construction. Similarly, the meshing relation of the gears 102 and 104 is not materially altered owing to the swing of the tool shaft as the movement of the gear 102 is smaller than that of the tool in proportion to their relative distances from the point about which the tool shaft 100 swings.

The operation of the above mechanism will now be described, it being understood that a downward movement of the treadle connected to the rod 54 will, by turning the lever 38, straighten the toggle constituted by its upper portion and the links 34 and thereby raise the sleeve 28, plunger 22 and disc 10. Firstly the nut 30 will be set with reference to the average thickness of the marginal portion of a shoe to be operated upon so that it can be inserted between the disc 10 and the wheel 18 when the treadle is in its raised position with the lever 38 against the stop 58. The rod 54 is also adjusted so that when the treadle is depressed to its full extent the disc 10 will be raised, owing to the straightening of the toggle referred to above, a distance just sufficient to cause the sole margin to be indented by the wheel 18 to the desired extent. The ma-

chine operator having placed a shoe in position will depress the treadle to its full extent and hold it down during the entire operation of indenting a shoe sole margin.

Until the disc 10, by carrying the sole margin 5 against the wheel 18, encounters resistance offered by the tool to further upward travel the pin 36 can continue moving around the boss 40 with a component of upward movement. As soon however as this upward movement of the pin 36 is resisted, further depression of the treadle, which is in opposition to the gravitational effect of the weight 46, will cause the lever 38 acting through the disc 40 to rock the arm 44 about its pivot 43 and cause the arm 44 and weight 46 to be lifted; and so long as this lifting persists the whole work-supporting mechanism composed of the disc 10, plunger 22, sleeve 28 and other members through which the effect of the weight 46 is transmitted will have a considerable degree of yielding but sluggish work-supporting resistance provided by the weight 46 which enables the work-support to follow, by gradual upward or downward movement, any variations in thickness of a shoe sole margin 20 being treated but does not respond to the rapid variations of pressure caused by the vertical reciprocation or vibration of the indenting wheel.

The provision of the stop 50, giving a definite point beyond which the weight 46 will not tend to raise the disc 10, enables sole margins which vary in hardness as opposed to thickness to be successfully treated. If some portion of a sole 35 margin happens to be considerably softer than the average, maintenance of full pressure between the wheel 18 and disc 10 might tend to squeeze such portion entirely out of its desired shape or even to cause the wheel to cut through some layer such as a welt or middle sole 40 composing the margin. Any substantial reduction of resistance of the sole margin to the pressure of the supporting disc and wheel will however allow the disc to rise, the arm 44 and weight 46 will then correspondingly descend and as soon as the 45 arm contacts with the stop 50 the effect of the weight and hence the indenting pressure is diminished or removed.

The above-described work supporting mechanism is adapted for use with either type of tool driving mechanism illustrated in Figs. 1 and 4. In either case, feed movement is imparted to a work-piece disposed between the tool or wheel and the work rest 10 owing to the continuous rotation of the tool or wheel, the work rest being mounted to rotate freely. Moreover, the success of the indenting operation is insured not only by the yielding resistance of the work rest to the indenting pressure of the tool or wheel but also by the regular and definitely controlled reciprocating or beating action of the tool or wheel which results from its being moved positively toward and away from the work, by either of the illustrated crank-operated mechanisms, as it is rotated.

Having thus described my invention, what I claim as new and desire to secure by Letters Patent of the United States is:

1. In an indenting machine, a rotatable work rest, an indenting tool, a tool shaft carrying said tool mounted for movement toward and away from said work rest, means for continuously rotating said tool shaft whereby a feed movement is imparted to a work-piece held against the tool 75

- by said work rest, and means for vibrating said tool shaft toward and away from the work rest to cause the tool to beat against the work-piece.
2. In an indenting machine, a work rest, an indenting tool, a tool shaft carrying said tool mounted for movement toward and away from said work rest, means for continuously rotating said tool shaft, and means for positively moving the tool shaft directly toward and away from the work rest to cause the tool to beat against a work-piece on said work rest.
3. In an indenting machine, a rotatable work rest, an indenting tool, a tool shaft carrying said tool mounted for movement transversely of its axis toward and away from the work rest, means for continuously rotating said tool shaft whereby a feed movement is imparted to a work-piece held thereagainst by said work rest, and connections acting upon said tool shaft to move it alternately in opposite directions normal to the surface of said work rest opposite to the tool.
4. In an indenting machine, an indenting wheel, a work rest, a shaft for supporting said indenting wheel mounted for movement toward and away from said work rest in a direction extending transversely of the axis of said shaft, means for continuously rotating said shaft, and crank-operated means for positively moving the shaft toward and away from the work rest to cause a rapid succession of blows to be imparted by the wheel to a work-piece on the work rest.
5. In an indenting machine, a rotatable work rest, an indenting wheel, a shaft carrying said indenting wheel mounted for movement bodily toward and away from the work rest in a direction extending transversely of the axis of the shaft, means for continuously rotating said wheel shaft whereby the wheel is caused to impart a feed movement to a work-piece presented thereto on said work rest, and mechanism for moving said wheel shaft toward and away from the work rest comprising a connecting rod, and a continuously rotating crank for operating said connecting rod.
6. In an indenting machine, a work rest, an indenting wheel, a member rotatably supporting said wheel mounted to slide toward and away from said work rest, means for continuously rotating said wheel, and means connected to said slide for positively moving it toward and away from the work rest thereby to cause the wheel to beat against a work-piece on said work rest with a rapid succession of blows.
7. In an indenting machine, a work rest, an indenting tool, a slide rotatably supporting said tool, said slide being mounted for reciprocating movement toward and away from the work rest, means for continuously rotating said tool, and means for rapidly reciprocating said slide toward and away from the work rest thereby to cause the tool to impart a succession of blows against a work piece on said work rest.
8. In an indenting machine, a work rest, an indenting tool, a slide rotatably supporting said tool, said slide being mounted for movement toward and away from said work rest, means for continuously rotating said tool, and mechanism for positively moving said slide toward and away from said work rest comprising a connecting rod and a crank for operating said connecting rod.
9. In an indenting machine, a work rest, an indenting wheel, a rotating shaft carrying said indenting wheel and mounted for swinging movement directly toward and away from the work rest, and means for positively swinging said shaft the as it is rotated thereby to cause the indenting wheel to beat against a work-piece on the work rest.
10. In an indenting machine, a work rest, an indenting wheel, said wheel being carried by a shaft mounted to swing about a point at its axis and remote from the wheel, and crank-operated means for positively swinging said wheel shaft as it is continuously rotated to cause said wheel to impinge upon a work-piece on said work rest with a rapid succession of blows.
11. In an indenting machine, a work rest, an indenting wheel, a rotating shaft carrying said indenting wheel and mounted for swinging movement, means for rotating said shaft, and mechanism for swinging said shaft to cause said wheel to beat against a work-piece on said work rest, said mechanism comprising a connecting rod and a crank for operating said connecting rod.
12. In an indenting machine, an indenting tool, a work rest mounted for movement toward and away from the tool, a support for said work rest including a weighted member, and connections between said rest and weighted member arranged normally to hold said rest in its inoperative position and operable in opposition to the gravitational effect of said weighted member to cause it to set up an indenting pressure between the tool and the work-piece which has been moved into engagement with the tool.
13. In an indenting machine, an indenting tool, a work rest mounted for movement toward and away from the tool, operator-controlled means for moving the work rest toward the tool to cause an indenting pressure to be exerted by the tool against the work piece on the work rest, and means acting upon said last mentioned means constructed and arranged to resist with a substantially constant force movement of the work rest throughout a limited range.
14. In an indenting machine, an indenting tool, a work rest mounted for movement toward and away from the tool, operator controlled means for moving the work rest toward the tool to cause indenting pressure to be applied to a work piece therebetween, and a yielding support for the operator controlled means arranged to resist the said indenting pressure with a substantially constant force throughout a limited range of movement of the work rest.
15. In an indenting machine, an indenting tool, a work rest mounted for movement toward and away from the tool, a toggle mechanism for moving said work rest toward the indenting tool thereby to cause an indenting pressure to be exerted on a work piece disposed therebetween, and a yielding supporting means for said toggle mechanism mounted and arranged to resist said indenting pressure gravitationally.
16. In an indenting machine, an indenting tool, a work rest mounted for movement toward and away from the tool, operator controlled means for moving said work rest toward said tool to cause indenting pressure to be exerted against a work-piece disposed therebetween, and a weighted lever, said operator controlled means being mounted on said lever for limited yielding movement about its fulcrum whereby a substantially constant force is applied by the work rest against the work as the work rest moves toward and away from the tool in response to variations in the thickness of the work.
17. In an indenting machine, an indenting tool, a work rest mounted for movement toward and

away from the tool, an operator controlled toggle for moving said work rest to carry a work piece thereon in operative relation to the tool, and a yielding support for said toggle constructed and arranged gravitationally to resist the indenting pressure of the tool when said toggle is straightened.

5 18. In an indenting machine, an indenting tool, a work rest mounted for movement toward and away from the tool, a weighted member mounted for movement in a direction having a vertical component, and means connecting said weighted member and work rest for moving a work-piece on the latter into operative relation with the tool whereby the center of gravity of said weighted member is raised and indenting pressure is applied to the work piece by the tool.

10 19. In an indenting machine, an indenting tool, a work rest, a weighted member, operator-controlled means interposed between said work rest and weighted member mounted and arranged successively to move said rest away from said member to carry a shoe on the rest into engagement with the tool and then to cause said member gravitationally to hold the work against the tool.

15 20. In an indenting machine, an indenting tool, a work rest, collapsible means for moving said work rest toward the tool in order to cause the latter to impart an indenting pressure against the work, and a weighted lever for supporting said collapsible means against said indenting pressure mounted to swing about its fulcrum in response to variations in the thickness of the work.

25 21. In an indenting machine, an indenting tool, a work rest, a weighted lever, and means carried by said lever for supporting said work rest normally in its inoperative position said means being

operable to carry a work-piece on said work rest into engagement with the tool whereby indenting pressure is imparted by the tool to the work.

22. In an indenting machine, an indenting tool, a work rest mounted for movement toward and away from the tool, means for moving said work rest to present a work piece thereon to the tool comprising an operator-controlled toggle mechanism, and a weighted member for supporting said toggle mechanism constructed and arranged to 10 resist the indenting pressure of the tool with a predetermined substantially constant force and to rise and fall in response to variations in the thickness of the work-piece.

15 23. In an indenting machine, an indenting tool, a work rest, means for supporting said work rest against the action of the tool comprising an operator-controlled toggle mechanism, and a weighted lever connected to said toggle mechanism constructed and arranged to allow the work 20 rest to yield in response to a predetermined amount of pressure between the tool and the work.

25 24. In an indenting machine, an indenting tool, a work rest mounted for movement toward and away from the tool, a weighted member mounted for movement in a direction having a vertical component, a stop for limiting the downward movement of said member, collapsible connections between said work rest and said weighted member, and means for straightening said collapsible connections whereby said weighted member is lifted from said stop and indenting pressure is applied to a work-piece between said work rest 30 and tool.

FRANK BYCROFT KEALL.
